DESIGN FOR A COVERED BUTTON

Jack Kowal, New York, N. Y.

Application April 9, 1936, Serial No. 62,035

Term of patent 3½ years

To all whom it may concern:

Be it known that I, Jack Kowal, a citizen of the United States of America, residing in the city of New York, county of Kings, and State of New York, have invented a new, original, and ornamental Design for a Covered Button, of which the following is a specification, reference being had to the accompanying drawing, forming part thereof,

Fig. 1 is a front view of a covered button showing my new design.

Fig. 2 is a rear view of a covered button as shown in Fig. 1.

Fig. 3 is a plan view of a covered button as shown in Fig. 1.

In Fig. 2 the black portion is a button inserted in the rear of the button.

The shaded portions connecting the buttons are elastic.

I claim:

The ornamental design for a covered button substantially as shown and described.

JACK KOWAL.
